(57) **CLAIM**

The ornamental design for a flashlight, as shown and described.

DESCRIPTION

FIG. 1 is a side perspective view of my new flashlight;
FIG. 2 is a left elevation thereof, the right side elevation
being a mirror thereof;

FIG. 3 is a front elevation view thereof, the rear elevation
being a mirror view thereof; and,

FIG. 4 is a top plan view thereof.

The broken line showing is for illustrative purposes only and
forms no part of the claimed design.
